UNITED STATES PATENT OFFICE.

LEO KNÖCHL, OF VIENNA, AUSTRIA.

SPRING HAMMER.

Application filed April 30, 1924, Serial No. 710,191, and in Austria May 9, 1923.

In spring hammers with eccentric or crank drives, arrangements are known which render possible a regulation of the strength of blow during the operation by means of varying the stroke of the tup or its position of height. These arrangements are adjusted directly by the workman and therefore call for a great exertion of power, or take up a great deal of time for their operation particularly in case of large hammers.

The object of the present invention is to provide a spring-hammer (laminated spring hammer, hammer with rubber or air buffers) in which the adjustment is rendered possible without any exertion of power and in a correspondingly quick manner in that an increase and decrease of the stroke of the tup is effected not directly by the workman but with the aid of a device, which makes use of the effect of the pressure-reversal of the reciprocating masses of the hammer.

Several modes of carrying out the present invention are shown by way of example on the accompanying drawings.

Figs. 1 and 2 show diagrammatically two different types of hammers. Fig. 3 shows a modified form of the hammer shown at Fig. 1.

Fig. 4 is a side view of a hammer with one embodiment of the control device shown partly in section.

Fig. 5 is a detail section of the control device taken at right angles to Fig. 4.

Fig. 6 shows a second and Fig. 7 a third embodiment of the control device according to the invention.

In Fig. 1 the tup 2, sliding in straight guides, strikes on the anvil block 1, the said tup being operated by a laminated spring 3, which swings about a pivot 4. The laminated spring 3 is oscillated by means of a connecting rod 6 operated by a rotary eccentric 5. The pivot 4 of the spring is movably arranged in a guide of the standard of the hammer, the adjustment being carried out in the direction of the arrows. However according to the invention the pivot of the spring is adjusted not directly by the control, but by means of the new control device.

In Fig. 2, 1 designates the anvil block, 2 the tup, 3 a lever with a curved spring, 4 its adjustable pivot, 5 the eccentric and 6 the connecting rod.

In Fig. 3, 1 designates the anvil block, 2 the tup, 3 the spring, 7 its fixed pivot, 6 the connecting rod, 5 the crank-pin of the driv-

ing crank, 8 a lever in the shape of a slide, whose pivot 4 is adjusted in the direction of the arrows by means of the new control device.

Figs. 4 and 5 illustrate the construction of a control device which consists of two oppositely acting obstructions and makes use of the effect of the pressure-reversal of the rods. A cylinder and valve casing 9 is secured to or formed in one piece with the hammer-standard and completely filled with liquid. The pistons 10 and 11 are connected with one another by a frame 12, which passes round the cylinder-casing 9 and slides in a straight guide (Fig. 5) and is provided with a pivotal axis 4 for the clamp 4^a of the laminated spring 3. The cylinder spaces 13 and 14 are in communication with a channel 15, which is furnished with two nonreturn valves 16 and 17, the latter being alternately raised by means of pins 18 and 19, which are actuated by a lever 20, connected in a convenient manner to the hand or foot control of the hammer.

The acceleration pressures of the reciprocating masses of the tup produce a continuous reversal of pressure in the axis 4 of the hammer-rods. In case the valves are closed the axis 4 will be at rest and the hammer-tup swings in the same height. If for instance the valve 16 is lifted, the liquid can pass from the cylinder-space 13 through the channel 15 into the space 14, but not in the opposite direction, as the valve 17 prevents a passage of the liquid in the opposite direction. Therefore at every reversal of the pressure only the upwardly directed acceleration pressure raises the frame 12, while the downwardly directed acceleration pressure is obstructed. As long as the valve 16 is lifted the frame moves step by step upwardly, this being the faster the more the valve 16 is opened. Thus during this operation the valve 17 acts as nonreturn valve and obstruction, and the valve 16 operates as regulating valve and liquid brake. In order to move downwardly the frame 12, the valve 17 is raised and the above operation takes place in the opposite direction.

Fig. 6 illustrates another construction of a device which makes use of the effect of the reversal of pressure. A cranked lever 21, whose axis of rotation 22 is fixed to the standard, is provided with a pivotal axis 4 for the hammer rods at one end and with two oppositely acting toggle lever friction-

ratchet gears 23 and 24 at the other end. A circular segment 25 is also secured to the hammer standard and the friction-ratchet gears rest against the said segment. A stop 26, arranged between the friction ratchet gears, is connected to the control of the hammer in such a manner, that it can be adjusted parallel with respect to the segment 25. In order that the friction ratchet gears cannot get clamped with respect to one another owing to the effect of the reversal of pressure and therefore could be released with great difficulty only, the same are held apart sufficiently far, so that a small back-lash arises and thereby an alternate clamping of the one friction-ratchet gear and a lifting of the other gear takes place at every reversal of pressure.

If the stop 26 is at a standstill the hammer-tup reciprocates in the same height, as the axis of rotation 4 of the rods carries out only a small movement which corresponds to the back-lash. In case the stop 26 is shifted by the control for instance to the right hand side, it will be followed to such an extent by the cranked lever 21 immediately an acceleration pressure acts upwardly on the axis of rotation 4, until it again comes into contact with the friction-ratchet gear 23 and after the overcoming of the back-lash the friction ratchet gear 24 will come into effect. After the subsequent reversal of pressure the upwardly acting acceleration pressure will produce a downward movement of the axis of rotation 4 of the rods which corresponds only to the small back-lash. After the following reversal of pressure the above procedure may be repeated in case the stop 26 is further shifted. In a similar manner a downward movement of the axis of rotation 4 of the rods may be carried out by shifting the stop 26 to the left hand side.

A third example of a device which makes use of the effect of the reversal of pressure is illustrated in Fig. 7. A rack 27 is guided in the hammer-standard and is furnished with an axis of rotation 4 of the hammer-rod and meshes with a toothed wheel 29, which is provided with a brake-pulley 28. Two oppositely acting toggle lever friction-ratchet gears 30 and 31 act as obstructions of the brake pulley 28 and are pressed onto the latter by means of two cranked levers 32 and 33, which are connected with one another by a spring 34. The friction-ratchet gears may be disengaged in the manner of shoe-brakes by means of a lever 26, one end of the latter being pivotally secured to a disengaging rod 35, while the other

end thereof is suitably connected to the hammer-control. The stops 37, 38 and 39 are rigidly secured to the hammer-standard and a weak spring 40 serves for providing the friction-ratchet gears with the initial friction, necessary for starting the self-obstruction.

On moving the disengaging rod 35 to the right hand side the same will contact with the cranked lever 33 and lift the friction-ratchet gear 31 in the manner of a shoe-brake, and in spite of the effect of the reversal of pressure the brake-pulley 28 can rotate clockwise only, as the friction-ratchet gear 30 prevents a rotation in the opposite direction. In this case the axis of rotation 4 moves downwardly, while in case the friction gear 30 is lifted the axis of rotation 4 will move upwardly.

I claim:—

1. In a spring hammer a tup, means for reciprocating the tup, means for controlling the reciprocating means including two oppositely acting members operatively connected to the reciprocating means and adapted one to prevent the rising and the other to prevent the lowering of the reciprocating means, and means for lifting one of the said members, to control according to requirement the reciprocating means.

2. In a spring hammer a tup, means for reciprocating the tup, means for controlling the reciprocating means including two oppositely acting hydraulic cylinders, a piston in each cylinder, said piston being connected to the reciprocating means, a channel for establishing communication between the working chambers of both cylinders, two non-return valves arranged in the channel, and means for lifting according to requirement one of the said valves, to control the direction of the fluid in the channel.

3. In a spring hammer a tup, means for reciprocating the tup, means for controlling the reciprocating means including two oppositely acting hydraulic cylinders, a piston in each cylinder, a frame operatively connected with the reciprocating means and surrounding the two pistons, a channel for establishing communication between the working chambers of both cylinders, two non-return valves arranged in the channel, and means for lifting according to requirement one of the said valves, to control the direction of the fluid in the channel.

In testimony whereof I affix my signature.

Inc. LEO KNÖCHL.
